ATTORNEY

UNITED STATES PATENT OFFICE

FREDERICK W. BLECKLEY, OF EAST ORANGE, NEW JERSEY

SUPPORTING DEVICE FOR KNIVES AND THE LIKE

Application filed December 31, 1928. Serial No. 329,579.

This invention relates to devices for supporting knives and the like.

One of the objects thereof is to provide a device of the above character of simple and inexpensive construction and neat and attractive appearance. Another object is to provide adequate and ready support for knives and tools of different thickness, shape and size, without special adjustment. Other objects thereof are to provide a holder which shall retain its efficiency under conditions of use, which is so constructed as to be long-lived and durable, and which is of rugged form without sacrifice of ready adaptability. Other objects will be in part obvious or in part pointed out hereinafter.

The invention accordingly consists in the features of construction, combinations of elements, and arrangement of parts as will be exemplified in the structure to be hereinafter described and the scope of the application of which will be indicated in the following claims.

In the accompanying drawing, in which is shown one of various possible embodiments of this invention,

Figure 1 is a perspective view of an embodiment of the invention;

Fig. 2 is in part a plan view of the device as shown in Fig. 1, and in part a cross section on the horizontal plane through the axis of the gripping member, which is shown both in plan and cross section;

Fig. 3 is a left end view of the device as shown in Fig. 1, with a portion of the end broken away; and

Fig. 4 is a cross section taken along the line 4-4 of Fig. 1.

Similar reference characters refer to similar parts throughout the several views of the drawing.

Referring to the drawing, there is shown at 1 an elongated rectangular box-like structure or bracket having extending therefrom upper and lower flanges 2 and 3 by means of which the said bracket may be secured to the surface of a wall or kitchen cabinet door, or in any other convenient and suitable location.

Attached to the front face 4 of said bracket

is an elongated tube retainer 5 which comprises a semicylindrical wall 6 which presents its concave surface to the surface 4 of the bracket member and is spaced therefrom by means of end extensions 7. Lugs projecting rearwardly from the extensions 7 pass through slots in the surface 4 of the bracket and are bent over, as shown at 8, to securely fasten the tube retainer 5 to the said bracket. The ends of the member 5 are left open, as shown at 9 in Fig. 1, for a purpose to be hereinafter mentioned.

Within the retainer 5 there is located a length of rubber tubing 10 which extends substantially the full length of said retainer, and is so mounted with respect to the face of the bracket 1 as to be substantially in tangential contact therewith along one side, as is shown at 11 in Fig. 3. The outer side of the length of tubing is supported within the tube retaining member 5 throughout substantially 180° of its periphery and snugly registers therewith.

In use, the operation of the tool-holder will be clearly understood by reference to Fig. 1 of the drawing, wherein is shown a plurality of knives thrust from above through the space lying between the tube retainer and the bracket, where their blades are resiliently engaged by the inner wall of the length of rubber tubing. As the tube lies in substantial contact with the face of the bracket, its surface is necessarily distorted or displaced by the blade of the knife or tool which it helps to support. It is to be noted, however, that this displacement is entirely local, for by the form and construction of the retaining member 5 the tubular member is supported over substantially the entire remainder of its surface. It results, therefore, that no distortion or permanent deformation of the tubing will take place unless knives are retained for long intervals of time in the same position and in contact with the same section of the tubular surface. In order to reduce to a minimum the likelihood of such local permanent distortion taking place, the ends of the retaining tube are left open so that one may introduce a finger and turn the piece of rubber tubing within its support so as to present new sur-

faces for contact with the tools. The open-ended construction affords also another advantage in that, should the tubing become dried out or lose its resiliency through aging, it may very simply be removed through either end of the retaining member and a new piece of tubing slipped in in its place. It is also to be noted that by reason of the close contact and support which the retaining member gives to the length of tubing, the latter may be of light construction, having thin walls and thus insuring not only great resiliency but less likelihood of becoming cracked or injured should knives or tools of unusual thickness be placed in the holder. Lighter tubing also means less material and a lower cost in manufacture. It is further to be noted that the resilient member is under no initial compression, and so long as it is not in use retains its natural tubular form.

From the foregoing it will be seen that applicant has devised a supporting device for knives and other tools well adapted to attain all of the aims and objects hereinbefore set forth. As the bracket and tube retaining member may be both and are preferably stamped out of thin sheet metal, they may be easily and inexpensively manufactured and will present a neat and attractive appearance when in use. As the tube retainer may be made of a diameter to take a standard size of rubber tubing, the resilient element of the device may not only be easily provided in manufacture, but replacements may be easily secured by the user. Any suitable means may be employed for securing the device, but, as shown herein, screws passing through the flanges 2 and 3 hold them to the surface upon which the device is supported.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

I claim:

1. In tool holding devices of the character described, in combination, a supporting member having a rigid surface, a tubular member yieldable in a direction transversely of its axis and positioned in proximate tangential relation to said surface, and means embracing said tubular member and holding it against bodily movement away from said surface.

2. In tool holding devices of the character described, in combination, a bracket having an elongated contact surface, a supporting member attached to said bracket, and a resilient member of substantially round cross-section held within said supporting member adapted to coact with said contact surface to hold tools therebetween, said round member

being resilient in a direction transversely to its axis.

3. In tool holding devices of the character described, in combination, a bracket having an elongated contact surface, a supporting member attached to said bracket, and a tubular member whose wall is yieldable, said tubular member being held within said supporting member and adapted to coact with said contact surface to yieldingly hold tools therebetween, said supporting member comprising a wall closely embracing a substantial portion of the wall of said tubular member for holding said member in operative position relative to said contact surface and for limiting distortion thereof to the tool-engaging wall portion thereof.

4. In tool holding devices of the character described, in combination, a bracket having an elongated contact surface, a supporting member attached to said bracket, and a member of substantially round cross-section held within said supporting member in proximate tangential relation to said contact surface to hold a tool therebetween, said supporting member being formed and adapted to permit endwise removal of said round member therefrom.

5. In tool holding devices of the character described, in combination, a bracket having an elongated contact surface, a supporting member comprising a substantially cylindrically curved wall spaced from and carried by said bracket, and a piece of rubber tubing positioned concentrically within said supporting member in close contact with said curved wall and in proximate tangential relation to said contact surface.

6. In tool holding devices of the character described, in combination, a bracket comprising a sheet metal member having a front plane surface and rearwardly bent flanges for securing said member to a wall, a supporting member carried by and in spaced relation to said bracket and presenting a cylindrical concavity toward said plane surface, and a resilient cylindrical member held closely within said concavity and positioned in proximate tangential relation to said plane surface.

7. In tool holding devices of the character described, in combination, a bracket comprising a member having a front plane surface and means for securing said member to a wall, a supporting member spaced from and attached at spaced points to said bracket and presenting a cylindrical concavity toward said plane surface, and a length of rubber tubing supported within said concavity and exposed, intermediate said spaced points, in proximate tangential relation to said plane surface.

8. In tool-holding devices of the character described, in combination, a member adapted to be attached to a supporting surface and having a front surface adapted to be engaged

by tools, a rubber tube resting substantially tangentially against said front surface, a rigid member curved substantially to fit over said rubber tube to support the latter and hold it against said front surface, and means holding said rigid member in spaced relation to said first-mentioned member to permit the insertion therebetween and between said front surface and said rubber tube of tools, said rigid member being shaped to permit the exposure of said rubber tube adjacent an end thereof to permit removal of said rubber tube.

In testimony whereof, I have signed my name to this specification this 18th day of December, 1928.

FREDERICK W. BLECKLEY.
